United States Patent Office.

ASA HOCKETT AND ALBERT C. HOCKETT, OF PLAINFIELD, INDIANA.

Letters Patent No. 82,837, dated October 6, 1868.

IMPROVED TILE-MACHINE.

The Schedule referred to in these Letters Patent and making part of the same.

TO ALL WHOM IT MAY CONCERN:

Be it known that we, ASA HOCKETT and ALBERT C. HOCKETT, of Plainfield, in the county of Hendricks, and in the State of Indiana, have invented certain new and useful Improvements in Tile-Machines; and do hereby declare that the following is a full, clear, and exact description thereof, reference being had to the accompanying drawings, and to the letters of reference marked thereon.

The nature of our invention consists in the construction and general arrangement of a machine for making tiles, which being less complicated than any others now in use, is more durable and has less friction, and can be repaired at any country blacksmith-shop, without being sent to the foundry. Besides, from its great simplicity, it saves expense, by lessening the number of men and horses necessary to work it.

In order to enable others skilled in the art to make and use our invention, we will now proceed to describe its construction and operation, referring to the annexed drawings, which form a part of this specification, and in which—

Figure 1 is a side view, part in section, of our machine.

Figure 2, rear view of the die.

Figure 3, front view of the same.

Figure 4, perspective of the gravel-screen; and

Figure 5 perspective of the follower, with end of slides.

A represents a frame, made of suitable material and dimensions, forming an oblong box, with both ends open. On the top of this frame is placed a tub or other circular vessel, B, the bottom of which is provided on one side with a slot or opening, which runs crosswise on the frame, as seen in fig. 1.

Over the top of the tub B is a bent cross-bar, C, in which the vertical shaft D has its bearing. This shaft runs through the centre of the tub and down through the frame A, forming there a crank, E, and has its lower bearing in the bottom of said frame.

Inside of the tub, a series of arms, F F, is placed on the shaft D, which serve to work the clay and pass it down through the opening in the bottom of said tub.

Inside of the frame A is a follower, G, which is attached to a sliding frame, H, at its front end, and at the rear end of this sliding frame is a vertical journal-bearing, I, from which a pitman, K, connects it with the crank, E. It will thus be seen that by turning the shaft, the follower G is made to move backward and forward alternately.

Near the front end of the frame A, and a little forward of the farthest point to which the follower G comes, is inserted a gravel-screen, L. This screen is inserted through a slot, made for that purpose, in the top of the frame, and consists of a frame, with upright bars, of suitable material and dimensions, and at suitable distance from each other, as shown in fig. 4.

In the front end of the frame or box A is placed the die M, which is so formed and arranged as to present a funnel-shaped surface to the clay forced through it by the follower.

To the upper end of the shaft D, the power with which the machine is operated is by any suitable means attached. When the shaft D is turned, the machine is so arranged that at the same time as the follower G is in rear of the opening in the bottom of the tub B, the lowest of the arms F forces the clay down through said opening. The sliding frame and follower then press the clay through the gravel-screen L, separating it from all stone or gravel that may be in the same. As, by repeated revolutions of the shaft, the space between the gravel-screen and the die gets filled with clay, the follower at last presses the clay through the die, forming the tile of any length desired.

We are aware that the several devices herein described, and their combination for the above purpose, is not new. We do not claim said devices specifically, or their combination; but having thus fully described our invention,

What we claim as new, and desire to secure by Letters Patent, is—

The arrangement of the frame or box A, tub B, sliding frame H, follower G, gravel-screen L, and die M, all constructed as described, and operating substantially as and for the purposes herein set forth.

In testimony that we claim the foregoing, we have hereunto set our hands, this 15th day of July, 1868.

ASA HOCKETT,
ALBERT C. HOCKETT.
